UNITED STATES PATENT OFFICE.

THOMAS K. PARRISH, OF RICHMOND, VIRGINIA.

ICE-CREAM FREEZER.

No. 830,166.

Specification of Letters Patent.

Patented Sept. 4, 1906.

Application filed February 26, 1906. Serial No. 303,032.

To all whom it may concern:

Be it known that I, THOMAS K. PARRISH, a citizen of the United States of America, and a resident of Richmond, county of Henrico, 5 State of Virginia, have invented certain new and useful Improvements in Ice-Cream-Freezer Gearings, of which the following is a full and clear specification, reference being had to the accompanying drawings, in 10 which—

Figure 1 is a vertical sectional view of an ice-cream freezer provided with my improved gearing. Fig. 2 is a perspective view showing the supporting-ring detached from the cross-bar; Fig. 3, a vertical central longitudinal section through a portion of the cross-bar supporting the gearing, and Fig. 4 a horizontal section on the line 4-4 of Fig. 3.

The object of this invention is to provide a 20 simple, strong, and easily repaired and inspected gearing for that class of freezers known as "triple-motion" freezers; and to the accomplishment of this object and such others as may hereinafter appear the invention 25 consists of the parts and combination of parts hereinafter fully described, and particularly pointed out in the appended claim, reference being had to the accompanying drawings, forming a part of this specification, 30 in which the same reference characters designate like parts throughout the several views.

Referring to the drawings annexed by reference characters, G represents the tub, K the can which incloses the beater-shaft J, 35 carrying the beaters j and the scraper-frame h, carrying the usual scrapers h', the upper tubular head H of the scraper-frame extending up through an opening k in the can-top. The upper end of the beater-shaft extends 40 up through the tubular head H and is provided with an angular shank at its extreme upper end, while the head H is also provided with an angular shank c².

The cross-bar supporting the gearing consists, as usual, of the semitubular parts a and a² and the central dome-like part A, and this cross-bar is removably fastened in place on top of the tub at one end by the usual lug g' and cam a³ and at the other end by the 50 usual legs a', engaging in the usual eyes g, fastened to the tub. The operating-crank d' is attached to the end of the driving-shaft d, which extends inwardly into the dome and carries the driving bevel-pinion D.

55 Fastened to the cross-bar by means of lateral ears b and suitable screws, which are

passed up through the ears into the cross-bar, is a splash ring or guard B, which depends a suitable distance to serve as a guard to prevent brine or ice being thrown up into the 60 gearing. Formed integral with this depending ring is a series of three radial wings b', which incline upwardly into the dome and which are connected at their upper ends by a vertical tubular bearing b², whose interior tapers upwardly. Fitting up into this bearing b² is a tubular shaft c of the lower gear-wheel C, the upper side of this wheel bearing against the lower end of the bearing b². Extending 65 up through the tubular shaft c is a shaft F, 70 which has attached to its upper end f the upper bevel-gear E, which gear rests upon the upper end of the tubular bearing b². This wheel E is formed with an upper tubular extension e, through which and the upper 75 end F of the shaft the transverse fastening-pin is passed. The shaft F is provided with an annular shoulder f', which engages an inwardly-extending shoulder c' on the tubular shaft c and in that manner holds said 80 tubular shaft in place. The lower end of shaft F is provided with a socket f² for engagement with the shank of the beater-shaft, and the lower end of the tubular shaft is provided with a socket c² for engagement with 85 the shank of the scraper-shaft, in the usual manner.

The usual frame k' is fastened to the bottom of the can and provided with the depending lugs k², which serve as supporting legs when the can is removed from the tub. The frame k' is provided with a depending central pivot, which has its bearing in a socket L, fastened to the bottom of the tub. The lower squared end of the beater-shaft 95 fits in a squared socket h², formed in the bottom of the can in the usual way. It will be observed that the rotation of the drive-shaft continuously in one direction serves to rotate the beater-shaft and the scrapers in opposite directions, the can being rotated with the beater-shaft, thereby obtaining the so-called "triple motion."

A special feature of the present invention lies in mounting the driven gears in a bearing 105 which may be readily removed from the dome for cleaning and repairing and at the same time afford the gears a durable and steady bearing or support. By extending the radial supporting-wings upwardly and 110 inwardly the greatest possible strength is obtained with a minimum of metal, and the de-

pend ing supporting-ring not only provides for readily removing the gears, but also serves as a splash-guard to the gears. Thus supporting the gears by an independent ring supported below the cross-bar enables the ring to be attached to the bar with the greatest degree of rigidity, since the lateral fastening lugs or ears may be located directly opposite each other in the vertical plane of the cross-bar, which enables them to be made as heavy and as long as the size of the machine may require, as is obvious. This manner of mounting the driven gears is especially advantageous in the larger sizes of freezers, as in these larger sizes the gearing is subjected to great strain when the cream becomes hard.

What I claim, and desire to secure by Letters Patent, is—

In an ice-cream-freezer gearing, the combination of a supporting-bar provided with a dome, a drive-shaft journaled in this cross-

bar and carrying a driving bevel-pinion, a depending annular splash-guard removably fastened to the under side of the bar and provided with a series of radial wings extending upwardly into the dome and connected to a vertical tubular bearing, a tubular shaft extending up into this bearing and carrying a bevel-gear and an angular socket at its lower end, a shaft provided with an angular socket at its lower end and extended up through said tubular shaft and carrying a bevel-gear at its upper end, this latter gear resting on the upper end of the aforesaid tubular bearing.

In testimony whereof I hereunto affix my signature, in the presence of two witnesses, this 24th day of February, 1906.

THOMAS K. PARRISH.
